[57] CLAIM

The ornamental design for an ice-box with a folding table, as shown and described.

DESCRIPTION

FIG. 1 is a front elevational view of the ice-box with a folding table showing my new design, the rear elevational view being a mirror image to the front elevational view; FIG. 2 is a top plan view thereof;

FIG. 3 is a right side elevational view thereof;

FIG. 4 is a left side elevational view thereof;

FIG. 5 is a bottom plan view thereof;

FIG. 6 is a right side elevational view of the ice-box with the table unfolded;

FIG. 7 a top plan view thereof;

FIG. 8 is a front elevational view thereof; and,

FIG. 9 is a perspective view thereof taken from the top, front and left sides.
